UNITED STATES PATENT OFFICE.

ARCHIBALD BANNATYNE, OF WATERBURY, CONNECTICUT, ASSIGNOR TO
THE WATERBURY CLOCK COMPANY, OF SAME PLACE.

DESIGN FOR A CLOCK-DIAL.

SPECIFICATION forming part of Design No. 18,306, dated May 15, 1888.

Application filed February 24, 1887. Serial No. 228,795. Term of patent 7 years.

To all whom it may concern:

Be it known that I, ARCHIBALD BANNATYNE, residing at Waterbury, in the county of New Haven and State of Connecticut, have invented and produced a new and original Design in Clock-Dials; and I do declare the following to be a full, clear, and exact description of the same, reference being had to the accompanying drawing, which forms a part of this specification.

The accompanying drawing is a view of my newly-designed clock-dial.

The leading feature of my design is a clock-dial bearing upon its face the representation of a musician.

The pictured musician B is represented as seated on a box, C, and as holding a banjo, D,

which is slung from his neck by a ribbon, E. The dial-plate A has openings F F and G.

I claim—

The design for a clock-dial herein shown and described, the same consisting of a clock-dial bearing upon its face the representation of a musician holding an instrument, and having the openings F F and G in the dial-plate, as set forth.

In testimony whereof I have signed this specification in the presence of two subscribing witnesses.

ARCHIBALD BANNATYNE.
